UNITED STATES PATENT OFFICE.

JESSE WARRINGTON, OF INDIANAPOLIS, INDIANA, ASSIGNOR OF ONE-HALF
TO THE NORDYKE & MARMON COMPANY, OF SAME PLACE.

BEARING FOR VERTICAL SHAFTS.

SPECIFICATION forming part of Letters Patent No. 600,816, dated March 15, 1898.

Application filed December 16, 1897. Serial No. 662,193. (No model.)

To all whom it may concern:

Be it known that I, JESSE WARRINGTON, a citizen of the United States, residing at Indianapolis, in the county of Marion and State 5 of Indiana, have invented certain new and useful Improvements in Bearings for Vertical Shafts, of which the following is a specification.

The object of my present invention is to 10 provide a suitable single bearing for vertical shafts of that class generally known as "step-bearings," which may be easily adjusted to bear properly upon the shaft at all times and take up all looseness resultant from wear.

15 A bearing embodying my said invention will be first fully described, and the novel features thereof then pointed out in the claims.

Referring to the accompanying drawings, which are made a part hereof and on which 20 similar letters of reference indicate similar parts, Figure 1 is a top or plan view of a bearing embodying my said invention, the shaft carried thereby being shown in section and all parts carried by said shaft serving to cover 25 or conceal, the bearing itself being removed; Fig. 2, a central vertical sectional view of the same as seen from the dotted line 2 2 in Fig. 1, the bearing-cover and a form of pulley carried by the shaft being shown in addition to 30 the parts shown in said Fig. 1; Fig. 3, a detail horizontal sectional view as seen from the dotted line 3 3 in Fig. 2, and Fig. 4 a detail vertical sectional view as seen from the dotted line 4 4 in Fig. 3.

35 In said drawings the portions marked A represent the outer shell or main chamber of the bearing structure; B B and C, bearing-plates within said chamber; D, an adjusting-rod, whereby the adjustment of the bearing- 40 plates is effected, and E a shaft carried by said bearing.

The outer shell or casing A is substantially in the form of an upright cylinder and preferably has an enlargement on one side at A', 45 (the form of which is best shown in Fig. 3,) although it might be made cylindrical by enlarging it somewhat. The form shown is preferred, however, as it is thus of less size and weight for the required capacity. This 50 shell is suitably mounted on an appropriate foundation, and I have provided spider-like

arms A², which may extend out a considerable distance, and thus give a very firm and substantial bearing, besides providing at the outer ends of said arms means for adjustment, 55 whereby the shaft may be always kept in an exactly vertical position. There are three of the bearing-plates, and consequently this shell may be considered as divided into thirds, each third equipped to receive and support 60 one of said plates. At suitable points in the interior on two of the three divisions as thus considered are bearing-ribs a, the bearing-surfaces whereof are segments of circles of less radius than the shell itself, the form of these 65 being best indicated in Fig. 3. Within the bottom I prefer to form an annular rim a' to receive and support the bearing-plates. Centrally within this rim and within a suitable depression in the interior surface of the shell 70 I place a bearing-plate a² of suitable metal to receive the end thrust of the shaft E and support the weight of said shaft and its load. Lugs c are formed in the interior of the shell 75 to guide and hold to proper position the bearing-plate C, as is best shown in Fig. 1.

Of the three bearing-plates two, B B, are provided with suitable projections which fit against the concave surfaces of the ribs a, as best shown in Figs. 3 and 4. This peculiar 80 formation and arrangement permits the bearing-plates to adjust themselves circumferentially to bear properly against the shaft and insures that the contact between the bearing-surfaces shall always be uniform. These two 85 bearing-plates have two bearing-points each, as shown, whereby they are maintained in fixed situation so far as their vertical arrangement is concerned.

The bearing-plate C, as shown in the drawings, is of a somewhat different exterior formation from the bearing-plates B and does not come in contact with the interior surface of the shell A, except at the lower end, where it rests on the annular rim a', and at points on 95 the sides, where it is guidingly held by the lugs c. It has a central transverse enlargement with which the end of the adjusting-rod D comes in contact, as will be presently described. The other bearing-plates being supported at or near the ends and this bearing-plate being supported at or near its center, 100

proper contact of the said bearing-plates throughout their length with the shaft is secured. Truss-like strengthening-ribs *r* on the back of this bearing-plate keep it from springing, so that there shall be no binding of the parts for lack of stiffness.

- The adjusting-rod *D* is mounted in a suitable screw-threaded extension *e*, secured to the side of the shell *A*, and its inner end comes 10 in contact with the bearing-plate *C*. As the bearing is intended to be continuously filled with oil, this adjusting-rod is shown as passing through a stuffing-box, by which any escape of oil is prevented. It is provided with 15 a lock-nut *d*, by which it can be locked in adjusted position. Said nut also holds the gland *g* of the stuffing-box to the proper position to insure the desired compression of the stuffing material.
- 20 The shaft *E* is of a common form and is mounted in the bearings described. It is shown only for purposes of illustration. Only a fragment thereof is shown in Fig. 2, the upper end, which carries or connects with the 25 mechanism to be driven, being broken away, as unnecessary to illustrate in this case, and the lower end being also broken out to show the interior of the bearing-plates. As shown in said figure, the bearing-plates are lined or 30 "babbitted" at the ends only, thus leaving the central portion free from contact with the shaft. This is because that in a bearing of this length it is unnecessary that the contact-surface should be continuous. I have shown 35 in Fig. 2 a pulley *P*, mounted on this shaft *E*, of a construction in which the center of the pull of the driving-belt is below the upper end of the bearing, which is obviously desirable

in a machine of this character where the shaft has no support at the upper end. In said 40 figure also I show a cover-plate *p*, which I have provided, the upper surface of which is somewhat funnel or hopper like and which is intended to exclude the admission of any extraneous matter to the interior of the bearing 45 structure shown and also to catch and convey into the bearing any oil which may drip from the machinery above.

Having thus fully described my said invention, what I claim as new, and desire to secure 50 by Letters Patent, is—

1. The combination, in a bearing for an upright shaft, of the outer shell, three bearing-plates within said shell, two of which are supported thereby at or near the ends, and an 55 adjusting-rod whereby the third is supported at or near its center.

2. The combination, in a bearing for an upright shaft, of an outer shell designed to contain three bearing-plates, ribs upon two interior sides of said shell at or near the upper and lower ends thereof and having concave surfaces of smaller radius than that of the shell itself, three bearing-plates positioned within said shell, two of which have convex 60 protuberances thereon adapted to fit the concave surfaces on said ribs, and an adjusting-rod adapted to support the third plate at a point at or near its center.

In witness whereof I have hereunto set my 70 hand and seal, at Indianapolis, Indiana, this 4th day of December, A. D. 1897.

JESSE WARRINGTON. [L. S.]
